CLAIM

The ornamental design for an ultraviolet disinfecting robot end effector, as shown and described.

DESCRIPTION

FIG. 1 is a top, front, left side perspective view of an ultraviolet disinfecting robot end effector, showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a top, front, left side perspective view thereof, showing the ultraviolet disinfecting robot end effector at a reduced scale and in a condition of use.

The broken lines depict portions of the ultraviolet disinfecting robot end effector and form no part of the claimed design. The broken lines showing the robot in FIG. 8 depict environmental subject matter that forms no part of the claimed design.
